UNITED STATES PATENT OFFICE.

FRED HARVEY BROWN, OF DALLAS, ASSIGNOR OF ONE-HALF OF HIS
RIGHT TO CARRIE D. BROWN, OF FORT WORTH, TEXAS.

CHILD'S CRIB.

SPECIFICATION forming part of Letters Patent No. 228,596, dated June 8, 1880.

Application filed March 18, 1880. (No model.)

To all whom it may concern:

Be it known that I, FRED HARVEY BROWN, of Dallas, in the county of Dallas and State of Texas, have invented certain new and useful Improvements in Children's Cribs; and I do hereby declare that the following is a full, clear, and exact description of the invention, which will enable others skilled in the art to which it appertains to make and use the same, reference being had to the accompanying drawings, which form a part of this specification, and in which—

Figure 1 is a side elevation. Fig. 2 is an end view, and Fig. 3 is a bottom plan.

Similar letters of reference indicate corresponding parts in all the figures.

My invention relates to suspended cribs or cradles for the use of children, and has for its object to construct a child's crib or cradle that may be easily operated, and in which means are provided for attracting the attention of the child occupying the crib while resting or preparing for sleep, substantially as hereinafter more fully set forth.

In the drawings, A is a suitably-constructed frame or support, in which the swinging crib B is suspended by the rods or wires C, of which one is attached to each corner of the crib.

In the top of the frame, at one end, is journaled a rock-shaft, D, which is provided with two strap-iron hangers or stirrups, E E, connected at their lower ends with the forward suspension-wires C C.

The shaft D has a crank, F, which is connected by a pitman, G, with the operating lever or handle H, that is pivoted upon one of the standards of frame A.

One or more cords, I, are passed from each of the suspension-wires C through screw-eyes J in the upper middle cross piece or brace of the supporting-frame, and have gaily painted

or gilded wooden balls K suspended from their lower ends. In the annexed drawings I have shown only four of these cords, each with a ball attached; but in practice I prefer to use eight cords and balls, each with its appropriate screw-eye, two cords being attached to each of the wires C.

In the lower part of the frame are arranged two or more parallel catgut (or metallic) strings, L L, transversely across the bottom of the swinging crib B, and held in place by the turning-pins M M.

Projecting downward from the bottom of the crib is a piece of whalebone or other suitable material, N, which plays upon the strings L L during the oscillations of the crib. This is operated by working the handle H, which is at a convenient height from the floor, and it will be seen that the crib vibrates in the long arc of an ellipse, so that it is always in a horizontal position. During the vibrations or rocking the painted or gilded balls K will alternately play up and down in sight of the child, so as to engage its attention.

Having thus described my invention, I claim and desire to secure by Letters Patent of the United States—

The combination, with the supporting-frame A, having screw-eyes J, and swinging crib B, suspended in said frame by rods C C, of the cords I, inserted through said eyes and provided each with one or more balls or weights, K, substantially as and for the purpose herein shown and set forth.

In testimony that I claim the foregoing as my own I have hereto affixed my signature in presence of two witnesses.

FRED HARVEY BROWN.
